US0D1091130S

(12) **United States Design Patent** (10) Patent No.: **US D1,091,130 S**
(45) Date of Patent: ** Sep. 2, 2025

(54) **EARPHONE CASE**

(71) Applicant: **SHENZHEN SHOKZ CO., LTD.**,
Shenzhen (CN)

(72) Inventors: **Zeteng Yan**, Guangdong (CN); **Lei Zhong**, Guangdong (CN); **Zhiqing Liu**, Guangdong (CN); **Chenxi Zhang**, Guangdong (CN); **Haofeng Zhang**, Guangdong (CN)

(73) Assignee: **SHENZHEN SHOKZ CO., LTD.**,
Shenzhen (CN)

(**) Term: **15 Years**

(21) Appl. No.: **35/520,315**

(22) Filed: **Mar. 15, 2023**

(80) **Hague Agreement Data**

Int. Filing Date: **Mar. 15, 2023**
Int. Reg. No.: **DM/229682**
Int. Reg. Date: **Mar. 15, 2023**
Int. Reg. Pub. Date: **Mar. 15, 2024**

(30) **Foreign Application Priority Data**

Nov. 10, 2022 (CN) 202230750739.X
Jan. 13, 2023 (CN) 202330055737.3

(51) LOC (15) Cl. **03-01**

(57) **CLAIM**

The ornamental design for an earphone case as shown and described.

DESCRIPTION

1. Earphone case
2. Earphone case
- 1.1 : Perspective
- 1.2 : Perspective
- 1.3 : Front
- 1.4 : Back
- 1.5 : Left
- 1.6 : Right
- 1.7: Top
- 1.8 : Bottom
- 2.1 : Perspective
- 2.2 : Perspective
- 2.3 : Front
- 2.4 : Back
- 2.5 : Left
- 2.6 : Right
- 2.7: Top
- 2.8 : Bottom
- 2.9 : Reference

(Continued)

The name of this design product: Earphone case; purpose of the product with this design: for storing earphones; the main points of the design of the product are the shape of the product; the picture or photo that best shows the main points of the design: reproduction 1.1 (perspective view); broken lines in reproduction 2.9 form no part of the claimed design.

1 Claim, 17 Drawing Sheets
